WALL OR LIKE PLUG

John Joseph Rawlings, London, England, assignor to The Rawlplug Company Limited, South Kensington, London, England

Application April 14, 1937, Serial No. 136,931
In Great Britain April 20, 1936

5 Claims. (Cl. 85—2.4)

This invention relates to wall or like plugs of the kind formed of fibrous material made up into a tubular structure by plaiting together or weaving strands of the fibrous material or by holding the strands in this formation by the aid of an adhesive or binding material, such plugs being intended to be inserted in holes in bricks, stone, plaster and like materials with a view to providing a suitable lining in the hole for the reception of a nail, screw or like fastening driven into the plug previously inserted in the hole and thereby ensuring a firm holding or retention of the said fastening therein.

The strands of fibrous material may in some cases enclose or be wrapped around wires, or the tubular structure may be provided with a lining of soft metal to reinforce the plug and to facilitate entrance of the screw.

When a plug is constructed by weaving or plaiting strands of fibrous material into a tubular form, on insertion into a prepared hole it tends to expand if tapped on the end, thus impeding its further entry into the hole, whilst if it is composed entirely of fibrous strands laid side by side, there is a tendency for it to split or open out.

The object of the present invention is to provide a plug which whilst possessing all the known desirable features of a fibre plug, especially a capability of expanding under the influence of a screw or nail driven into it, nevertheless has a substantial resistance to expansion or splitting if tapped on its end, for example, with a hammer, in order to drive it into a hole in which the plug fits closely.

According to this invention the plug is stiffened longitudinally by the incorporation of a number of metal wires in such a manner that they exercise practically no restraining influence on the expansion of the plug when a screw or nail is driven into it, but give greater rigidity to the plug.

In the accompanying drawing, Figures 1 to 4 show diagrammatically various embodiments of the invention.

For the purpose set forth, wires 3 may be wrapped helically around individual strands 4 of fibre and the strands plaited together to form a wall plug, as shown in Figure 1; or strands 6 of fibre with exterior wire wrappings 5 may be laid side by side to form a tube and held in this formation by an adhesive or like binding material as shown in Figure 2. In a further arrangement according to this invention, as shown in Figure 3, wires 7 are plaited or braided with

fibrous strands 8 and if desired the latter may be given a twist in one direction whilst the wires have a twist in the opposite direction.

The pitch of the helical coils or plaiting of the wires is preferably not less than the pitch of a wood screw which the plug is intended to receive.

In view of the greater rigidity of a plug constructed in this manner, it is desirable in some cases to provide means whereby rotation of the plug is avoided when inserted loosely in a hole, and this may be achieved by arranging the wire so that it provides exterior ribs which, if the wire is suitably chosen, will also assist the plug to resist withdrawal from the hole. The wire may also be arranged to form exterior ribs or slight protuberances from the surface of the plug by previously forming it into a zig-zag shape as shown in Figure 4, where there is diagrammatically illustrated a single strand 9 of fibrous material having wires 10 and 11 arranged around the strand so as to provide relatively long strips of wire on the exterior and interior faces of the plug.

In accordance with this invention the wires may advantageously be arranged so that a large proportion of bare metal is exposed on the outer surface of the plug, and the wires may be made some of soft metal or alloy, and some of hard metal or alloy, to ensure a maximum grip on the wall of the hole into which the plug is inserted and to ensure a maximum resistance to the withdrawal of the plug longitudinally from the hole.

I claim:

1. A wall plug for the reception of driven fastenings comprising fibrous material, and wires incorporated with the fibrous material, the wires being plaited with the fibrous material in such a manner that parts of the wires are exposed on the outer surface of the plug.

2. A wall plug for the reception of driven fastenings, comprising strands of fibrous material arranged to form a tubular plug, and wires wound spirally around a plurality of the individual strands.

3. A wall plug for the reception of driven fastenings, comprising strands of fibrous material arranged to form a tubular plug, and metal wires, each of said wires being in conjoint cooperative relationship with an individual fibrous strand to form a composite fibre wire strand, parts of the wire being exposed on the exterior of the plug.

4. A wall plug for the reception of driven fastenings, comprising strands of fibrous material,

and metal wires each wound helically around an individual fibrous strand, the fibrous strands being interwoven together to form a tubular structure.

5. A tubular wall plug for the reception of driven fastenings, comprising strands of fibrous material and a plurality of metal wires, each of said wires being in conjoint cooperative rela-

tionship with an individual fibrous strand, such relationship consisting in arranging the wire around the strand so as to provide relatively great lengths of wire on the exterior and interior faces of the strand when forming part of the 5 tubular structure.

JOHN JOSEPH RAWLINGS.
